UNITED STATES PATENT OFFICE.

THOMAS R. KENNEDY AND EDWARD J. KING, OF ROCHESTER, NEW YORK,
ASSIGNORS TO CO-OPERATIVE FOUNDRY CO., OF ROCHESTER, NEW
YORK, A CORPORATION OF NEW YORK.

DESIGN FOR A STOVE.

No. 38,799.

Specification for Design.

Patented Sept. 10, 1907.

Application filed July 31, 1907. Serial No. 386,489. Term of patent 7 years.

To all whom it may concern:

Be it known that we, THOMAS R. KENNEDY and EDWARD J. KING, citizens of the United States, and residing at Rochester, in the county of Monroe and State of New York, have invented a new, original, and ornamental Design for Stoves, of which the accompanying drawing is a representation.

The figure is a perspective view of a stove showing our new design.

We claim:

The ornamental design for a stove as herein shown.

THOMAS R. KENNEDY.
EDWARD J. KING.
